GEORGE T. TRUNDEL, JR., OF CLEVELAND, AND BURTON G. CARLSON, OF CLEVELAND HEIGHTS, OHIO.

ADJUSTING MECHANISM FOR BAG-TUBE CUTTERS.

Application filed January 9, 1922. Serial No. 527,956.

To all whom it may concern:

Be it known that we, GEORGE T. TRUNDEL, Jr., and BURTON G. CARLSON, citizens of the United States, residing at 3153 Sycamore Road, Cleveland, Ohio, and 1705 Belman Road, Cleveland Heights, Ohio, respectively, in the county of Cuyahoga, have invented a certain new and useful Improvement in Adjusting Mechanism for Bag-Tube Cutters, of which the following is a full, clear, and exact description, reference being had to the accompanying drawings.

This invention is concerned with paper bag forming mechanisms, and is particularly directed to improvements in tube forming machines.

In the art of bag making, the bags are first formed into tubular blanks by a tube forming machine which is usually arranged to receive a paper roll at one end from which the web passes to a preliminary slicing or shearing mechanism. The web then passes over mandrels or tube forming guides which cause the side edges of the sheet to be folded inwardly in an overlapping relation. A strip of adhesive material is usually impressed on one of the overlapping surfaces of the sheet before the sheet is completely folded into a tubular form. The tube thus formed then progresses through feed rolls which serve the double purpose of moving the web from the roll through the various mechanisms, as well as to press the tube into a flattened condition. A second shearing mechanism is usually driven in synchronism with the feed rolls which effects the final shearing of the tubes into uniform bag lengths or blanks as the tube is advanced from the feed rolls. The shearing of the tube into bag lengths is thus effected in two operations, namely; the central portion of the web is sheared or punched before the sheet has progressed through the tube forming mechanism and the final shearing is completed after the tube has passed through the feed rolls; it is essential therefore, that both shearing mechanisms be driven in synchronism so that the sheared edges effected by the second shearing operation will register with the sheared edges effected by the first shearing operation.

In the tube forming machines now in use, driving means are provided connecting the

shearing mechanisms and the feed roll whereby tubes of uniform length are produced at a high rate of speed. If it is desired to change the length of the tubes being formed on the machine the gearing ratio between the feed rolls and both shearing mechanisms is changed, whereby the feed rolls will move the tube or sheet through the shearing mechanisms at a greater or a lesser speed depending upon whether the length of tubes is to be longer or shorter. Considerable difficulty, however, has been encountered in readjusting the shearing mechanisms, when the machine is being changed to obtain properly timed cutting action on the moving web.

The general object of the present invention therefore, is the provision of novel adjusting means associated with the shearing mechanisms, whereby the machine may be quickly and accurately adjusted to produce various lengths of bag tubes.

A more specific object of this invention is the provision of means for driving the two sets of shearing mechanisms in cutting synchronism which includes a drive shaft parted intermediate of the shearing mechanisms, and joined by adjustable coupling means, whereby the ends of the shaft may be angularly displaced to cause a corresponding angular displacement between the shearing blades of the respective mechanisms, thus changing the timing (and the position of the cuts on the web) of one of the shearing mechanisms relative to the other.

A further object is the provision of indicating means associated with said shaft coupling means whereby the angular adjustment being made may be read directly on a dial associated with the coupling means.

Other objects will become apparent from the description hereinafter set forth which refers to the accompanying drawings. The essential characteristics are summarized in the claims.

In the drawings, Fig. 1 is a side elevation of a tube forming machine; Fig. 2 is a diagrammatic representation of the shearing mechanisms and with the tube shown traveling therebetween along a horizontal plane; Fig. 3 is a similar representation showing the mechanisms adjusted to form

bag tubes of greater length than the tubes being formed by the setting illustrated in Fig. 2. Fig. 4 is a fragmentary plan view of the paper web with one end thereof formed into a tube; the shearing mechanism and feed rolls being omitted; Fig. 5 is a cross sectional view of a coupling and indicating means; Fig. 6 is a cross sectional view taken along the line 6—6 of Fig. 5; Fig. 7 is a fragmentary view of one of the coupling members.

A tube forming machine such as I have illustrated in Fig. 1 is usually comprised of a frame 10 supporting a tube forming bed 11. The frame usually has means for supporting a large roll of paper (not shown) from which the paper web P is drawn. Suitable braking mechanism is usually provided for maintaining a uniform tension in the paper web.

The web is drawn over a roll 14 which may be comprised of rubber or other resili- 25 ent material. A shearing knife 15 is usually disposed above the top surface of the web and may be mounted on a rotatable shaft member 16. The shearing member 17 is adjusted to strike the top surface of the web; the circle described by this shearing member being such that the cutting edge 30 thereof will penetrate the web and effect a shearing or slitting, such as is illustrated at A in Fig. 4. The slit thus effected will be present in only one side of the tube which is subsequently formed.

As the web progresses through the machine it is drawn past forming bars 18 and 19 rigid with the bed 11 with the result that an inward folding of the side edges of the web is effected such as is illustrated at B 40 in Fig. 4. As the web progresses further it is drawn through final folding members 20 which effect the final tube formation of the web. One of the folded edges of the web is usually coated with an adhesive 45 whereby the tube is permanently defined as it passes through feed rolls 22 and 23.

As the completed tube is advanced from the feed rolls to the discharge end of the machine, it passes through a final shearing 50 mechanism comprised of a knife member 24 disposed above the tube and a coacting platen member 25 disposed below the tube. These shearing members are mounted on rotatable shafts 26 and 27 respectively and 55 are actuated by gears 28 and 29, which are of equal diameter. The gear member 29 is driven by a gear 30 mounted on the shaft member 31 on which a driving pulley (not shown) may also be mounted. The feed 60 rolls may be driven through change gears actuated from the same source as the gears 28 and 29. Hence the shaft 31 may also carry a change gear 32 which is arranged to drive an intermediate gear member 33 adjustably mounted on a bracket member 34.

This gear member drives another intermediate gear member 35 which actuates the feed roll gears 36 and 37.

Connecting mechanism is provided to drive the shearing member 24 and the shearing member 15 in timed relation which includes a longitudinal shaft 42. A bevel gear 40 is rigidly mounted on the shaft 31 which meshes with a similar gear 41 mounted on 70 cludes a longitudinal shaft 42. A bevel gear 43 is mounted on the upper end of this shaft which drives a bevel gear 44 mounted on the end of the shaft 16. When adjusting the machine to form a longer or shorter tube it has been the practice heretofore to replace 80 the gear 32 with a different sized gear and then change the angular relation of the shearing members by resetting the gears 28 and 29 relative to the gear 30. The shearing members 15, 28 and 29 are driven at such 85 a speed that the linear velocity thereof is considerably greater than the highest velocity which may be imparted to the paper web when the machine is adjusted to make tubes of maximum length; the web is thus 90 prevented from gathering or catching up to the cutting edges of the shearing members.

In the diagrammatic illustration shown in Fig. 2, it will be noted that the distance between the point where the first shearing member 15 acts upon the web to the point where the shearing members 24 and 25 effect the final shearing thereof, is divided into 95 equal spaces which correspond to the length 100 of the tube being formed. These equal spaces, however, would be of greater length if the feed rolls 22 and 23 were actuated at a greater rate of speed, other conditions remaining the same.

In Fig. 3 the diagram illustrates the condition which would exist if the rate of speed of the feed rolls were increased. To increase the feed roll speed it would be necessary, however, to replace the gear 32 with a 110 larger gear, thus requiring a resetting of the intermediate gear members 33 and 35.

I have devised a very efficient and simple means which may be associated with the driving means whereby the necessary adjustment between the two sets of shearing mechanisms may be quickly and accurately effected. To this end I have divided the shaft member 42 into two members, 42^a and 42^b. One of the members (42^a) may have a clutch member 50 secured to the end thereof which is arranged to positively grip the adjacent 115 end of the other shaft member 42^b. This clutch member may be secured to the shaft member 42^a by any suitable means such as pins 54.

The clutch member 50 may be formed somewhat in the manner of a chuck collet having tapered portions 51 which are adapted to be contracted upon the shaft member 120 125 130

42^b by a member 52 having an internal coniform surface which is adapted to engage the outer surface of the spring portions 51. The member 52 may have an interiorly 5 threaded portion adapted to engage an exteriorly threaded portion of the member 50, whereby turning of the member 52 will either cause a gripping of the spring portions 51 upon the shaft member 42^b or cause 10 a releasing thereof, as desired.

For the purpose of aligning the adjacent ends of the shaft members 42^a and 42^b, I prefer to form a reduced portion 56 upon the end of one of the shaft members which 15 is adapted to fit a suitable bore formed in the end of the other shaft member. It is evident that by releasing the coupling means one shearing mechanism may be adjusted to any angular position relative to 20 the other by turning either end of the shaft 42 with a wrench while the other end is stationary.

It will be noted from the diagram shown in Fig. 3 that the position of the shear members 24 and 25 has been advanced from that 25 illustrated in Fig. 2. The position illustrated in heavy lines, is the position to which these members have been adjusted in order to obtain a proper registration of the 30 shearing edges of the members 24 and 25 with the sheared slits effected by the member 15 when the tube is being moved at a greater rate of speed.

For comparative purposes the original 35 positions of the shear members are illustrated in dot and dash lines. It is evident that the shear members 24 and 25, if acting in the position as illustrated by the dot and dash lines, would not register with the sheared slits effected by the member 15.

In order to properly adjust the members 24 and 25 to the position shown by the full lines in Fig. 3, it has been necessary heretofore to remove the gear 30 and rotate the 45 gears 28 and 29 to the desired position, after which the gear 30 was replaced. This method involved considerable annoyance and frequently required several trial settings before an accurate adjustment was obtained between the first and second shearing mechanisms.

To further facilitate the accurate setting of the two mechanisms, I have provided a dial member 58 which may be rigidly 55 secured to the shaft member 42^b. A pointer member 59 may be secured to the end of one of the spring portions 51 of the spring 50. Hence the pointer member is in rigid relation with the shaft member 42^a and the 60 exact amount of angular adjustment between the shearing members 24 and 25 may be read or indicated on a graduated face 60 of the dial 58, as illustrated in Fig. 6. If desired, the dial face may be graduated 65 and marked with the exact positions to

which the mechanism should be adjusted in order to form various lengths of bags; hence the size of the bag may be marked adjacent the corresponding angular mark on the dial.

A paper tube machine equipped with my invention may be readily adjusted to form various lengths of bags by changing the speed of the feed rolls, after which the two sets of shearing mechanisms may be 70 properly adjusted to have the cutting elements thereof act upon the paper web along coordinated lines transversely of the web. A correct adjustment may be immediately obtained when changing the paper tube machine to cut a different length of bag, to that which it had been previously cutting by maintaining the gears 28 and 29 in a definite position as well as the bevel gears 43 and 44 during the time the gear 32 is 80 being changed and the intermediate gears 35 and 36 are being reset. The proper angular adjustment of the cutting elements may then be obtained by turning either one of the shaft members 42^a or 42^b; the amount 85 of adjustment being read by observing the position of the pointer 59 in relation to the dial 58. If the dial is provided with graduations which correspond to the various bag 90 tube lengths, the machine can produce the proper adjustment of the cutting elements which may be immediately obtained by angularly displacing one of the shaft members 95 until the pointer is not at the proper dial mark.

It is evident that the mechanism as illustrated comprises, in effect, a couple represented by a preliminary shearing mechanism and a couple represented by a second or final shearing mechanism with means for feeding material therethrough disposed intermediate thereof; the couples being actuated by driving a mechanism provided with adjustable means for determining the time of action of the respective couples.

While the embodiment of my invention as illustrated in the drawings is a preferred form when applied to a paper tube forming machine, it is obvious that the adjusting means may be comprised of any suitable elements which may release the driving means to permit adjustment of one of the couples, while the other couple remains stationary.

Having thus described our invention, we 120 claim:—

1. In a machine for forming paper bag tubes, the combination of mechanism for shearing slits intermediate the edges of the paper web being formed into the tube, feed rolls for drawing the web through said slitting mechanism, a second mechanism for completing the shearing of the tubes into uniform lengths or blanks, means for driving said shearing and said slitting mecha- 125 130 135

nisms in synchronism whereby the second named shearing mechanism will completely shear the tube, said shearing being effected in registration with the slits previously formed in the paper web by the first named shearing mechanism, and adjustable means associated with said synchronizing means for angularly displacing one shearing mechanism relative to the other when the speed of said feed rolls is changed.

2. In a tube forming machine of the character described, the combination of a shearing mechanism adapted to effect a partial shearing of a paper web into uniform lengths, a pair of feed rolls adapted to act upon the web and draw it through said shearing mechanism, a second shearing mechanism adapted to sever the completed tube along lines transversely of the tube, and in registration with said previously formed slits, and means for driving said first named and said second named shearing mechanisms in synchronism including a driving shaft connecting the respective shearing mechanisms, said driving shaft comprising two aligned shaft members joined by adjustable coupling means whereby the first named mechanism may be adjusted angularly relative to said second named mechanism.

3. In a tube forming machine of the character described, the combination of mechanism for effecting a preliminary slitting of a paper web, a pair of feed rolls for drawing the web therethrough, a second shearing mechanism adapted to completely sever the tube into blanks of uniform lengths, means for driving said mechanisms in synchronism, means for changing the speed of said feed rolls whereby the web may be moved through the machine at a greater or lesser speed while the speeds of said shear-

ing mechanisms remain constant, and adjustable means associated with said synchronizing means whereby the periods of the shearing action of the respective mechanisms may be changed.

4. In a paper tube forming machine having a preliminary shearing mechanism and a final shearing mechanism, the combination of means for driving said shearing mechanisms in synchronism including connecting mechanism comprising aligned shaft members having the adjacent ends thereof joined by adjustable coupling means whereby said shearing mechanisms may be adjusted to act upon the tube at different periods.

5. In a paper tube forming mechanism having a preliminary shearing mechanism and a final shearing mechanism, the combination of means for driving said shearing mechanisms including a connecting shaft parted intermediate said mechanisms and joined by adjustable coupling means whereby said shearing mechanisms may be adjusted to act upon the tube at different periods.

6. In a paper tube forming machine, mechanism for effecting a partial shearing of a paper web passing therethrough, a second mechanism adapted to act upon the web along lines coordinating with said preliminary partial shearing, a common driving means for positively actuating both sets of mechanisms, said driving means including adjustable coupling means whereby the time of acting upon the paper web of one set of shearing mechanism may be adjusted relative to the other.

In testimony whereof we hereunto affix our signatures.

BURTON G. CARLSON.
